To all whom it may concern:

Be it known that I, Katheryn Rost, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

The characteristic feature of my design resides in the combination on the specific dress disclosed of the drawn work blouse having blocks of fagotting arranged on the front and on the sleeves as shown in association with the particular skirt as shown.

I claim:

The ornamental design for a dress, substantially as shown and described.
